CARRIAGE RETURN MECHANISM FOR
WRITING MACHINES

Oscar J. Sundstrand, Hartford, Conn., assignor
to Underwood Elliott Fisher Company, New
York, N. Y., a corporation of Delaware

Application December 30, 1938, Serial No. 248,553

16 Claims. (Cl. 197—66)

This invention relates to typewriters and other record making machines and more particularly to a power operated carriage return mechanism for such machines.

One object of the present invention is to improve the construction and mode of operation of power operated carriage return mechanisms for record making machines and to produce a novel and improved mechanism by which the carriage of such a machine may be selectively returned by power to any one of two or more returned positions.

Another object of the invention is to produce, for machines of the above class, a carriage return mechanism for causing the return of the carriage by power to any one of two or more returned positions, having stopping devices for causing the discontinuance of the return movement of the carriage selectively with the carriage in the desired position, in which novel and improved mechanism is provided for holding said devices in position during the return of the carriage and for releasing said devices after the return movement of the carriage has stopped.

With the above and other objects in view the invention consists in a carriage return mechanism embodying the novel and improved features, constructions and combinations of parts herein-after described and particularly pointed out in the claims, the advantages of which will be readily understood and appreciated by those skilled in the art.

The invention will be clearly understood from the accompanying drawings illustrating the invention in its preferred form and the following detailed description of the constructions therein shown.

In the drawings:

Figure 1 is a perspective view illustrating certain parts of a typewriting machine of the Elliott Fisher type embodying the invention.

Figure 2 is a perspective view taken from the rear of the machine and illustrating particularly the carriage return mechanism.

Figure 3 is a view in side elevation, partly in section, illustrating the key carriage, the carriage return mechanism and certain devices for controlling said mechanism and the stopping of the return movement of the carriage.

Figure 4 is a detail view in side elevation, partly in section, illustrating the devices for controlling the carriage return mechanism and the stopping of the return movement of the carriage shown in Figure 3, with certain of said parts in different positions.

Figure 5 is a view similar to Figure 4 illustrating certain of the parts in still different positions.

Figure 6 is a detail view in front elevation illustrating mechanism for holding the stopping devices for stopping the return movement of the carriage in position during said return movement.

Figure 7 is a view similar to Figure 6 illustrating certain of the parts in different positions.

Figure 8 is a detail perspective view illustrating one of the parts of the mechanism shown in Figures 6 and 7 detached from the machine.

Figure 9 is a detail sectional view illustrating certain parts of the mechanism shown in Figures 6 and 7, and

Figure 10 is a detail view in side elevation illustrating a portion of the mechanism shown in Figures 3, 4, and 5 with certain of the parts in different positions.

The invention is illustrated in this application as embodied in a machine having the same general construction, arrangement and mode of operation of parts as the machine disclosed in the patent to Foothorap, No. 1,904,127, dated April 13, 1933.

Referring to the drawings, a flat platen 1 is mounted in a rectangular platen frame comprising a pair of parallel side bars 2 suitably supported on a standard, not shown. A portion of each bar is toothed to form a rack engageable by traction gears 4 fast on a shaft 6 extending transversely of the side bars and supported by bearings in brackets, one of which is shown at 8, projecting upwardly from the rear portions of the side members of the rectangular line space frame 10. This shaft also carries wheels 9^a engaging tracks 9 formed on the side bars 2 and the front rail 12 of the line space frame is likewise supported by wheels, (not shown) engaging said tracks to enable the line space frame to move forwardly and rearwardly.

The rear and front cross rails 11 and 12 support a key carriage 14 shown in dot and dash lines in Figure 1 for travel across the platen 1 in letter spacing direction and return, on front and rear wheels engaging rails 12 and 11, respectively, of the line space frame, of which wheels the front wheels 15 only are indicated.

The key carriage contains the customary key actions, ribbon mechanism and controls for the carriage escapement, not necessary to illustrate, but disclosed in the U. S. patent to Foothorap No. 1,203,519, dated October 31, 1916. The usual spring barrel 16 is mounted on the line space

frame 10, a tape 18 connecting the spring barrel with the key carriage 14 to draw the carriage toward the right in letter spacing direction under control of the escapement mechanism.

Power drive

The key carriage 14 may be manually returned to the left hand margin from any point to which it has been advanced in letter spacing direction, but to relieve the operator of the work of returning the carriage, a motor 20 is provided, conveniently mounted on a casting, (not shown) secured to and projecting rearwardly from the rear rail 11 of the line space frame 10 with which it travels.

Referring to Figure 2 of the drawings, power from the motor is taken from the worm 22 fast on the motor shaft 24 and meshing with a worm gear 26 having a friction clutch connection 28 with a countershaft 30 journaled in the casting and extending forwardly beneath a carriage return rack 31 secured to the flanged rear end of an apron 32 projecting from the deck 34 of the key carriage 14.

A wide carriage return pinion 36 journaled on the forward end of the countershaft 30 and axially movable along the shaft, meshes with the teeth of the carriage return rack 31 at all times, the return pinion having a peripherally grooved collar 38 terminating at its rear end in a driven clutch member 40 normally disengaged from a driving clutch member 42 fast on the countershaft.

The free end of a clutch shift finger 44 lies in the groove in the sliding rotatable collar 38, the finger being secured to a clutch shifting shaft 46 journaled in the motor support casting. A clutch shifting arm 48 fast on one end of the clutch shifting shaft 46 is provided with a lateral locking lip 50 normally engaged by a locking latch 52 journaled on a trip shaft 54 extending across the machine and supported in bearings projecting from the back of the rear rail 11 of the line space frame. A fan-shaped trip arm 56 secured to the trip shaft 54 extends rearwardly between two studs 58 and 60 projecting respectively from the hooked latch 52 and from the clutch shifting arm 48, a normally tensioned spring 62 connecting the two studs to form a yielding link therebetween and normally maintaining the hooked latch 52 engaged with the clutch shifting arm 48 to retain the clutch members 40 and 42 disengaged.

Control of automatic carriage return mechanism

Curved arms 55 projecting upwardly and forwardly from the trip shaft support a tripping bail 64 toothed at its opposite ends and rocking with the shaft 54. Mounted on the right hand end of the tripping bail is a cam block 66 arranged to be engaged by a roll 96 projecting downwardly from the carriage apron.

In the normal positions of the parts, the hooked latch 52, normally engaged with the lip 50 of the clutch shifting arm 48, retains the trip shaft 54 and its tripping bail 64 in their rear-most positions. As the carriage 14, travelling in letter spacing direction, advances the printing point toward the extreme right hand margin of the work sheet, the roll 96 wipes across the inclined face of the cam block 66 and rocks the bail forwardly, thereby rocking the trip shaft 54 in a clockwise direction, Figure 3.

The cam block 66 is mounted for sliding adjustment on the trip bail 64 and is pivotally con-

nected by a link 98 with the right hand marginal stop 100 which is adjustably mounted on the right hand end of the carriage escapement rack 102.

The rearwardly projecting trip arm 56 is swung upwardly by the rocking movement of the trip shaft to disengage the hooked latch 52 from the clutch shifting arm 48 and, in so doing, additionally tensions the spring 62, which spring, acting as a tension link, rocks the clutch shifting shaft 46 and its clutch shifting finger 44 counter-clockwise, Figure 3, to slide the driven member 40 of the carriage return clutch along the countershaft 30 into engagement with the driving member 42, the carriage return pinion 36 being of sufficient width to maintain its engagement with the carriage return rack throughout the clutch shifting action.

The motor 20, if of the constantly running type, will then drive the carriage in contra-letter spacing direction, toward the left hand margin. In the machine illustrated in this application the motor is of the intermittent type, as shown and described in Patent No. 1,904,127, and the motor circuit is normally interrupted. The means for controlling the motor circuit is as follows.

The normally open circuit for the motor includes a source of power 104 and a switch 106, the latter comprising stationary and movable contacts 108 and 110.

The movable contact 110 is mounted on the swinging switch arm 112 pivoted at 114 and connected by a slotted link 116 with a depending switch controlling arm 118 fixed to the trip shaft 54, the switch arm 114, with its contact, being normally held apart from the stationary contact 108, by the clutch engaging spring 62.

When the roll 96 on the carriage rocks the tripping bail 64 and its trip shaft 54 is a clockwise direction, Figure 3, the switch controlling arm 118 fast on the trip shaft will force the slotted link 116 rearwardly to enable the spring 120 which has less power than the spring 62, to rock the switch arm 112 and engage its contact 110 with the stationary contact 108, thereby closing the circuit through the motor to transmit power thereto.

Where a continuously running motor is employed, the switch mechanism and its control are omitted.

As the carriage approaches the end of its return movement under the influence of the motor 20, the tripping bail 64 is swung back rearwardly to its normal position. During this operation, the tripping arm 56 is pressed against the stud 60 on the clutch shifting arm 48 and rocks the arm, together with the clutch shaft 46 and clutch finger 44 in a clockwise direction, Figure 3, to cause the finger to disengage the driven clutch member 40 from the driving clutch member 42 thereby disconnecting the motor 20 from the travelling carriage 14.

The spring 62 tends to draw the hooked latch 52 downwardly as the clutch shifting arm 48 is swung downwardly, and when the arm 48 reaches a certain position, the latch snaps down over the lip 50 on said arm to lock the clutch shift mechanism, and hence the clutch members, in disengaged positions.

At the same time, the switch control arm 118 on the trip shaft 54, through the link 116, swings the switch arm 112 and its contact 110 away from the stationary contact 108, to interrupt the motor circuit, the spring 62 maintain-

ing the movable switch contact out of engagement with its stationary contact.

The mechanism for swinging the tripping bail 64 rearwardly as the carriage approaches the end of its return movement will be hereinafter described.

All of the mechanisms above described have substantially the same construction arrangement and mode of operation as the corresponding mechanisms of the machine illustrated and described in applicant's pending application Serial No. 149,571, filed June 22, 1937.

Partial carriage return

The present machine is provided not only with a mechanism for automatically returning the carriage to position to begin the typing of a line, but is also provided with mechanism for stopping the carriage in fully returned position or in either of two partial return positions at different distances to the right of its fully returned position. In carrying out the invention, three keys are mounted on the key carriage 14 in place of the single key shown and described in Foothorap Patent No. 1,904,127. By the respective actuation of these keys the carriage return mechanism will be thrown into operation and the return movement of the carriage will be arrested with the carriage in any one of three different return positions, the stop position being selected by the actuation of the appropriate key.

Referring to Figures 3, 4 and 5 of the drawings, the keys controlling the return under power of the carriage from any advanced position to a selected precedent position are mounted on the travelling carriage 14 and arranged in a novel manner to enable the selection of any of several precedent positions to which the carriage may be returned. The machine is provided with a key lever 122, the actuation of which causes the engagement of the carriage return clutch and the closing of the motor switch to effect the return movement of the carriage. The key lever 122 which extends along the left side wall of the carriage is pivoted at 124 to the rear portion of the carriage frame, and is acted upon by a coiled spring 123 which normally maintains the same in elevated position. This key lever extends forwardly to a point adjacent the keyboard of the key carriage and terminates in an upwardly projecting stem extending through a slot in a guide plate 126 secured to the inclined keyboard frame, the stem having a transverse stop pin 128 to limit the extent of depression of the key lever. A key 130 is fixed to the upper end of said stem and the depression of this key causes the return of the carriage to its limiting left hand position.

A bell crank lever 132 pivoted at 124 concentrically with the key lever 122, depends from this pivot pin, the depending arm constituting a support for an extension 134 adjustably secured, as by a bolt and slot connection 136 and a pivot 138 spaced therefrom, to the depending arm of the bell crank. The extension is slotted as at 140 to embrace a stud 142 on a radial arm 144 secured to a horizontal shaft 146 journaled in bearings on the key carriage frame. This shaft extends part way toward the right hand side of the key carriage and at its inner end carries an arm 148 depending through a slot in the apron 32 to a point in proximity to and behind the trip bail 64.

The remaining shorter arm of the bell crank 132 projects forwardly substantially parallel with

and below the key lever 122 and the free end of said arm is provided with a lip 150 formed thereon to contact normally a rigid headed pin 152 projecting from the left side of the key carriage 14 which arrests the parts at one extreme of their movement.

A restoring spring 154 (Figure 2), encircling the shaft 146, yieldingly retains the arm 148 withdrawn from the trip bail 64, the headed pin 152 serving to limit the clockwise rotation of these parts under the influence of the spring 154 and to confine the parts against lateral displacement.

A by-pass pawl 156 pivoted at 158 between the ends of and depending from the key lever 122, is turned clockwise by a spring 160 until its free reduced end is arrested by contact with the fixed pin 152, in such position as to lie in line with the lip 150 on the short arm of the bell crank 132. The key lever 122, when depressed, forces the reduced end of the by-pass pawl 156 against the lip 150 of the short arm of the bell crank 132, and rocks the bell crank clockwise (Figures 3, 4 and 5). This movement of the bell crank, through arm 144 and shaft 146 rocks the arm 148 counter-clockwise against the trip bail 64 to actuate said bail to close the carriage return clutch 40, 42 and the motor circuit switch 106 so that the motor is energized and the carriage is returned toward the beginning of a line.

The depression of the key lever 122 to its fullest extent brings the sharply inclined edge 162 of the by-pass pawl into wiping contact with the limit pin 152 which operates to cam the by-pass pawl off from the lip 150. When this occurs the spring 154 restores the arm 148, shaft 146, arm 144, and bell crank 132 to their normal positions irrespective of and uncontrolled by the key lever 122.

To enable the carriage to be arrested in different return positions, each short of a complete return to the left hand marginal position, the machine is provided with a second key lever 164 having a stem projecting upwardly through the guide plate 126 above the stem of the key lever 122 and having a key 166 fixed to the upper end of said stem and with a third key lever 168 having a stem projecting upwardly through said guide plate above and to the rear of the stem of the lever 164 and having a key 170 fixed to the upper end of said stem. The key lever 168 extends downwardly and rearwardly across the left hand end of the key carriage 14 and its lower end engages behind a guide plate 172 secured at its rear edge to the outer face of an abutment 174 depending a predetermined distance below the left hand lower corner of the key carriage 14.

The inner face of the guide plate 172 is vertically grooved, to accommodate slidingly a check stop 176 secured to the lower end of the key lever 168. The lever 168 is acted upon by a coiled return spring 178 which normally holds the lever yieldingly in its uppermost position.

The lever 164 is pivoted at 180 on the lever 168 and, upon being depressed, is arranged to actuate the lever 168 through an eccentric 182 fixed to, and rotatably adjustable on, the lever 164 and engaging in a slot 183 in the lever 168. This slot provides lost motion between the lever 164 and the lever 168, the amount of which may be regulated by adjusting the eccentric 182.

In order that the lever 122 may be depressed to throw the carriage return mechanism into operation by the depression of either the key lever 164 or the key lever 168, the lever 122 car-

ries a pin 184 secured in an upwardly projecting portion of the lever and engaged by the lever 164 during the downward movement of the latter lever. This pin engages in a slot 186 in the lever 164 and forms a guide for said lever but permits the lever 122 to be depressed freely independently of the lever 164.

The pin 128 constitutes a stop limiting the downward movement of the levers 164 and 168 as well as the lever 122. The upward movement of the lever 164 is limited by the engagement of a stop face 188 formed on said lever with the under side of the guide plate 126. This limits also the upward movements of the lever 122 and of the lever 168.

The mechanism cooperating with the check stop 176 to arrest the return movement of the carriage has the same construction, arrangement and mode of operation as the corresponding mechanism illustrated and described in applicant's application Serial No. 149,571. Said mechanism comprises a draft rod 190 extending transversely of the line space frame. This rod is T-shaped in cross section and is arranged to slide in a channel formed by the rear rail line 11 of the line space frame, the web 192 projecting forwardly therefrom and the carriage escapement rack 102 which is secured to the forward edge of said web.

The left hand end portion of the draft rod 190 is toothed for a considerable distance and arresters 194, 196 and 198 of different heights are adjustably arranged on the draft rod to be engaged respectively by the fixed abutment 174 and the check stop 176 to arrest the carriage during its return movement at any one of three precedent positions and also to effect a line spacing operation incident to its return to any such precedent position. The arrester 194 of least height is located farthest to the right and the arresters 196 and 198 of successively greater heights are mounted on the draft rod in corresponding order to the left of the arrester 194. These arresters preferably have substantially the same construction as illustrated and described in applicant's application Serial No. 149,571, to enable them to be readily adjusted longitudinally on the draft rod.

The left hand end of the draft rod 190 passes through an aperture in a rearwardly turned slotted projection 200 on the left hand end of a slide 202 extending therefrom toward the right along the front face of the carriage escapement rack 102 to which the slide is connected by headed fastenings 204 engaging in slots 206 in 55 the slide. The slide operates to guide the draft rod in its endwise travel and prevents it from canting in its channel.

The draft rod is provided at its right hand end with a threaded portion 208 passing through a 60 block 210 secured to the forward face of an arresting plate 212, the draft rod being secured to said block by means of nuts 214 threaded on the rod and located upon opposite sides of the block. The arresting plate 212 is provided with parallel slots 216 and 218 through which pass respectively a headed fastening 220 and a stub shaft 222 to support and guide the plate.

The arresting plate 212 is formed with a beak 224 which projects toward the left from the upper left hand edge of the plate into position to collide with a forwardly extending fixed stop 226 (Figure 1) rigidly secured to the right hand end of the rear rail 11.

A coiled spring 228 secured at one end to the 75

fixed stop and connected at its opposite end to the draft rod 190 yieldingly retains the arresting plate 212, the draft rod and the slide 202 at their right hand limits of travel as determined by contact of the left end wall of the slot 216 in the arresting plate with its guiding and supporting stud or headed fastening 220.

When the operator, at any point in the advance of the carriage, desires to return the carriage to its limiting left hand position or to give a full return movement to the carriage, he depresses the key 130 and key lever 122 to their limiting positions determined by the engagement of the stop pin 128 with the guide plate 126.

15 During the downward movement of the lever, the bell crank 132 is actuated to engage the carriage return clutch and to close the switch of the motor circuit after which the pawl 156 is cammed off the lip 158 of the bell crank lever so that the key lever exercises no further control of the bell crank and the parts operated thereby. After actuation by the key lever, the parts of the clutch engaging mechanism and the switch closing mechanism between the arm 148 and the clutch and switch are maintained in position until the carriage approaches the end of its return movement. The check stop 176 is not depressed by this operation but remains in its uppermost position.

20 During the return movement of the carriage, the fixed abutment 174 passes over the graduated arresters 194 and 196 and finally engages the highest arrester 198, the location of which on the draft rod determines the beginning of a line of writing.

25 The abutment 174, upon contact with the abrupt right hand face of the arrester 198, forces the arrester to the left and with it the draft rod 190 and arresting plate 212, tensioning the return spring 228, until the beak 254 impinges against the fixed stop 226 which positively arrests further travel of the draft rod and the arrester 198 leftwardly and hence arrests the carriage 14 in its predetermined extreme leftward position to define the left hand margin and the beginning of the writing line.

30 A slight play is arranged between the right hand end of the draft rod and the block 210 to enable the escapement to lock the carriage at a uniform point upon each return of the carriage.

35 As the draft rod is moved to the left by the final movement of the carriage, the carriage return clutch is disengaged and the switch of the motor circuit is opened by mechanism herein-after described.

40 When the operator desires to arrest the return movement of the carriage in a position to the right of the full return position as determined by the arrester 196, he depresses the key 166. The depression of the key depresses the lever 122 through the engagement of the lever 164 with the pin 184 to throw the carriage return mechanism into operation and to close the motor circuit, the movement of the lever 122 and the lever 164 being limited by the engagement of the pin 128 with the guide plate 126. During the downward movement of the lever 164, after a predetermined amount of movement of the lever 164 independently of the lever 168, the eccentric 182 engages the lower side of the slot in the latter lever and said lever is then moved downwardly to project the stop 176 downwardly to a position such that it will clear the arrester 194 but will engage the arrester 196 during the return movement of the carriage. During the

return movement of the carriage, the check stop 176 passes over the arrester 194 and engages the arrester 196 as the carriage approaches the end of its return movement and slides the draft rod to the left in the same manner as before until the movement of the carriage is finally stopped by the engagement of the beak 224 on the slide 212 with the fixed stop 226.

When the operator desires to arrest the return movement of the carriage in a position to the right of the partial return position determined by the engagement of the check stop with the arrester 196, he depresses the key 170. The depression of this key depresses the lever 164 through the engagement of the eccentric 182 with the upper side of the slot 184 in the lever 168 and the depression of the lever 164 depresses the lever 122 through the engagement of said lever 164 with pin 184, the movement of the levers being limited by the engagement of the pin 128 with the guide plate 126. The depression of the lever 122 throws into operation the carriage return mechanism and the motor switch closing mechanism as before. The downward movement of the lever 168 projects the stop 176 to a lower position than that into which it is projected by the depression of the lever 164 to cause the stop to engage the arrester 194 during the return movement of the carriage. As the carriage executes its return movement under the action of the power mechanism, the check stop 176 engages the arrester 194 thereby moving said arrester and the draft rod 190 to the left until the movement of the carriage is stopped by the engagement of the beak 224 with the stop 226.

It is highly desirable that the mechanism for stopping the return movement of the carriage in the two partial return positions should be maintained operative after a quick depression and release of either of the keys 166 and 170. Otherwise, it would be necessary for the operator to maintain each of these keys in depressed position during the return of the carriage in order to stop the carriage in the desired partial return position. In order to secure this result, mechanism is provided for holding the check stop 176 in either of the positions into which it is projected by these keys after the quick depression and release of the key.

The mechanism for holding the check stop in position comprises a latch bar 230 pivoted upon a stud 232 secured in a projection on the lever 168 and depending therefrom in the manner clearly shown in Figures 6 and 7. The latch bar is loosely pivoted on the stud 232 so that not only can the stud turn freely within the latch bar, but the latch bar can swing freely in a vertical plane containing the axis of the stud. The latch bar extends downwardly from the lever 168 through an opening 234 in a guide plate 236 formed on a bracket 238 secured to the side of the deck 34 of the key carriage. The latch bar is formed with notches 240 and 242 arranged to receive alternatively a catch 244 formed by the beveled edge of the guide plate 236 to hold the latch in either of two depressed positions. The latch bar is acted upon by a leaf spring 246 secured to the stud 232 and bearing against the outer face of the latch bar which normally maintains the latch bar in engagement with the edge of the catch 244.

When the key 166 is depressed to its limiting position, the latch bar is depressed to a point at which the catch 244 engages in the lower notch 240 to hold the lever 168 in position to locate the

check stop 176 to engage the arrester 196 during the return movement of the carriage. When the key 170 is depressed to its limiting position, the latch bar is depressed into position to cause the catch 244 to engage in the upper notch 242 to hold the lever 168 in position to locate the check stop 176 to engage the arrester 194 during the return movement of the carriage.

The latch bar is arranged to hold the lever 168 in position until the carriage has completed its return movement. Thereafter the latch bar is automatically actuated to release the catch 244 from the notch in the latch bar in which it is engaged and the lever 168 is then moved upwardly to its upper limiting position by the return spring 178.

The mechanism for releasing the latch from engagement with the catch 244 comprises a lever 248 provided at its upper end with trunnions 250 projecting from opposite sides thereof and engaging in bearings in the lateral wings 252 formed on the bracket 238, the lever being arranged to engage the lower end of the latch bar when swung to the left from the position shown in Figure 6. The lever is provided with a weight 254 attached to the lower end thereof to increase the force of inertia on the same at the end of the carriage movement. The lever 248 normally rests against a plate 256 secured by screws 258 to the lower deck or type ring 260 of the carriage, which plate determines the position of rest of the lever.

Figure 6 shows the position of the parts when the key 166 has been depressed to its limiting position thereby causing the catch 244 to engage in the lower notch 240 in the latch lever to hold the lever 168 in depressed position. With the parts in the positions shown in this figure, when the carriage return mechanism is thrown into operation by the depression of the key, the parts retain their positions until the movement of the carriage is arrested in the manner above described. When the movement of the carriage is stopped, the lever 248 swings to the left under inertia thereby swinging the latch bar to the left to disengage the same from the catch 244. The release of the latch allows the lever 168 and check stop 176 to be restored to their normal upper positions.

When the key 170 is depressed to its limiting position, the catch 244 engages in the upper notch 242 in the latch bar to hold the lever 168 in depressed position during the return movement of the carriage. When the movement of the carriage is stopped, the lever 248 is swung under inertia as before to disengage the latch bar from the catch and release the lever 168 and the check stop, allowing these parts to be restored to their normal upper positions.

The latch bar 230 is adjustably suspended from the lever 168 in order to enable the position assumed by the check stop 176 upon the release of the keys 166 and 170 to be accurately determined. In the construction shown, the latch bar is loosely pivoted on an eccentric bearing sleeve 261 adjustably mounted on the screw stud 232 and provided with a disk 263 at one end thereof by which it may be rotatably adjusted. The spring 246 is mounted on the screw stud between the head of the same and the sleeve 261, and the sleeve and spring are both held securely in position by the tightening of the screw which is threaded into the lever 168.

When the carriage has been stopped by the engagement of the check stop with the arrester

194 and the latch has been released, the movement of the draft rod 180 to the right has moved the arrester to the right beyond the check stop. Then, if it is desired to return the carriage to the next partial return position, the key 166 is depressed. This will project the check stop into position to engage the arrester 196, and the carriage will be moved farther to the left and stopped by the arrester 196. In a corresponding manner, when the return movement of the carriage has been stopped by the arrester 196 and it is desired to return the carriage to its fully returned position, the key 130 is depressed to cause the return of the carriage until its return movement is stopped by the engagement of the abutment 174 with the arrester 198.

The disconnection of the motor from the carriage and the opening of the motor switch is automatically effected regardless of the extent of return travel of the carriage by a mechanism adapted to function just prior to the arrest of the carriage at any of its completely or partially returned stations. The said mechanism comprises a floating thrust bar 262 slidably supported adjacent its left hand end in an eye 264 formed in a bracket secured to and projecting from the adjacent vertical bracket 8 on the line space frame. The thrust bar is slotted at its right hand end as at 266 to ride on the rear end of a stud 268 projecting rearwardly from and travelling with the arresting plate 212. The left hand end of the thrust bar is arranged to engage an inclined cam face on a member 270 secured to the right hand end of the trip bail 64 in the path of travel of the thrust bar.

The length of the slot 266 in the thrust bar is less than the distance normally between the beak 224 and the fixed stop 226. Therefore, as the arresting plate 212 is drawn to the left by contact of the abutment 174 with the arrester 198 or by contact of the check stop 176 with either of the arresters 194 or 196, the supporting stud 268 will travel idly along the slot 266 of the thrust bar until just prior to the arrest of the plate 212 by contact of the beak 224 with the stop 226, the supporting stud 268 reaches the left end wall of the slot 266. Thereafter, the continued movement of the arresting plate 212 shifts the thrust rod to the left against the inclined face of the contact member 270 on the trip bail and rocks the trip bail back to its normal position, thereby disconnecting the shiftable driven clutch member of the carriage return clutch from the driving clutch member and (if required) interrupting the motor circuit.

In order to operate the latch bar to release the lever 168 in the event that either of the keys 166 or 170 is held depressed during the carriage return and until after the movement of the carriage is arrested, a manually operable latch bar actuating lever 272 may be provided as shown in Fig. 3. This lever is pivoted at 274 on the side wall of the key carriage and is provided at its rear end with an extension 276 bent in a cam shape and arranged to engage the inner face of the latch bar. When it is desired to release the latch bar from the catch 244, the forward end of the lever 272 is depressed thereby swinging the inclined face of the extension 276 back against the inner face of the latch bar and forcing the latch bar outwardly to release the same from the catch 244 and thereby release the lever 168. The lever 272 is acted upon by a coiled spring 278 which restores said lever to its normal position. The movement of 75

the lever 272 in opposite direction is limited by stop pins 280 mounted in the side wall of the carriage.

5 The machine is preferably provided with a line spacing mechanism having the same construction as the line spacing mechanism of the machine illustrated and described in applicant's pending application Ser. No. 149,571. This mechanism operates, when the return movement of 10 the carriage is stopped with the carriage at any one of the predetermined marginal positions, to impart automatically a line spacing movement to the line space frame.

15 Having explained the nature and objects of the invention and having specifically described a construction embodying the invention in its preferred form, what is claimed is:

1. In a record making machine, a carriage movable in opposite directions across the machine, means for moving the carriage in one direction to letter space, power mechanism for imparting return movements to the carriage, means for arresting the movement of the carriage in any one of two or more returned positions, means for throwing in said power mechanism and for positioning certain parts of said arresting means to stop the carriage selectively in the required position, mechanism for holding said parts of the arresting means in operative position during the return of the carriage until the movement of the carriage is completely arrested and machine controlled means for automatically releasing said holding mechanism after the movement of the carriage is arrested with the carriage in any one of said positions.

2. In a record making machine, a carriage movable across the machine in opposite directions, means for moving the carriage in letter spacing direction, power operated mechanism for imparting return movements to the carriage, mechanism for stopping the return movement of the carriage with the carriage in a predetermined partially returned position, comprising a movable stopping device, a manipulative device for throwing in said power operated mechanism and for positioning said stopping device to stop the carriage, means for holding said stopping device in stopping position during return movement of the carriage to stopping position and machine controlled mechanism for releasing said holding means immediately after the movement of the carriage is stopped.

3. In a record making machine, a carriage movable in opposite directions across the machine, mechanism for moving the carriage in one direction during the record making operation, power mechanism for imparting return movements to the carriage, means for arresting the movement of the carriage with the carriage in a fully returned position, a device for arresting the movement of the carriage with the carriage in a partially returned position, mechanism for simultaneously throwing in said power mechanism and for positioning said device to arrest the carriage, means for holding said device in operative position during the partial return movement of the carriage until the movement of the carriage is completely arrested and machine operated mechanism rendered operative by the arrest of the carriage for automatically releasing said holding means after the movement of the carriage is arrested.

4. In a record making machine, a carriage movable in opposite directions across the ma-

chine, means for moving the carriage in one direction during the record making operation, power mechanism for imparting return movements to the carriage, a device for stopping the carriage during its return movement in a predetermined partially returned position, a key and connections for throwing in said power mechanism and for positioning said device to stop return movement of the carriage means for holding said device in stopping position during the return movement of the carriage until said movement is completely stopped and mechanism under machine control, rendered operative by the stopping of the carriage and operating automatically after the movement of the carriage is stopped and prior to the next advance of the carriage, for releasing said holding means.

5. A record making machine having, in combination, a carriage, means for moving the carriage in one direction across the machine during the record making operation, power mechanism for imparting return movements to the carriage, stopping means for stopping the return movement of the carriage with the carriage in a partially returned position, comprising a movable stop, manipulative devices for simultaneously throwing the power means into operation and for moving the stop into operative position, a latch for holding the stop in stopping position during the entire return of the carriage to stopping position and mechanism controlled by the machine and operating automatically in response to the stopping of the carriage for releasing the latch after the stopping of the carriage.

6. A record making machine having, in combination, a carriage, means for moving the carriage in one direction across the machine during the record making operation, power means for imparting return movements to the carriage, stopping means for stopping the return movement of the carriage with the carriage in a partially returned position, comprising a movable stop, manipulative means for simultaneously throwing the power means into operation and for moving the stop into operative position, a latch for holding the stop in stopping position during the return of the carriage and devices moving with the carriage during its return and operated by inertia after the stopping of the carriage for releasing the latch.

7. In a record making machine a carriage movable in letter spacing direction and return, means for moving the carriage in letter spacing direction, power mechanism for imparting return movements to the carriage, devices for stopping the return movement of the carriage alternatively with the carriage in a fully returned or in a partially returned position, means for throwing in said power mechanism for the return of the carriage to either of said positions, mechanism for positioning one of the stopping devices for the stopping of the carriage in a partially returned position, mechanism for holding the latter stopping device in operative position during the partial return movement of the carriage and means mounted on the carriage and operated by inertia after the movement of the carriage is stopped for releasing said holding mechanism.

8. In a record making machine, a carriage movable in opposite directions across the machine, means for moving the carriage in one direction to letter space, power mechanism for imparting return movements to the carriage, a device for stopping the carriage in a partially returned position, manually controlled means for si-

multaneously throwing in said power mechanism and for positioning said stopping device to stop the carriage in said position, mechanism for holding said stopping device in stopping position during the return of the carriage until after the stopping of the carriage and automatic mechanism for releasing said holding mechanism in response to the stopping of the carriage.

9. A record making machine having, in combination, a carriage movable in opposite directions across the machine, means for advancing the carriage during the record making operation, power means for imparting return movements to the carriage, a settable device for causing the stoppage of the carriage in a predetermined return position, manually controlled means for setting said device, mechanism for retaining said device in operative position during return movement of the carriage to stopping position and machine controlled means operating automatically in response to the stopping of the carriage for actuating said retaining mechanism to release said device after the movement of the carriage is stopped with the carriage in said position.

10. In a record making machine, a carriage movable across the machine in advance and return directions, mechanism for advancing the carriage, power mechanism for imparting return movements to the carriage, a device arranged to be set by the operator to discontinue the return movement of the carriage with the carriage in a predetermined return position, means under control of the operator for setting said device, mechanism for retaining said device in operative position during return movement of the carriage and means moved with the carriage during its return and operated by inertia after the movement of the carriage is discontinued for causing the restoration of said device to normal position.

11. A record making machine having, in combination, a carriage movable across the machine in letter spacing direction and return, means for moving the carriage in a letter spacing direction, power mechanism for imparting return movements to the carriage, a device for effecting the arrest of the return movement of the carriage with the carriage in a predetermined return position, mechanism for setting said device in operative condition, retaining means for holding said device in said condition during the return of the carriage, and means rendered operative by the stopping of the carriage for causing the restoration of said device after the return movement of the carriage has stopped.

12. A record making machine having, in combination, a carriage movable in opposite directions across the machine, means for advancing the carriage during a record making operation, power means for imparting return movements to the carriage, a manually settable device for discontinuing the return of the carriage with the carriage in a predetermined return position, means under control of the operator for throwing in said power means, mechanism for holding said device in set position during the return of the carriage and means comprising a weighted lever carried by the carriage and operated by inertia upon the discontinuing of the return movement of the carriage for causing the return of said device to its normal position.

13. In a record making machine a carriage movable across the machine in opposite direc-

tions, means for moving the carriage in letter spacing direction during a record making operation, power operated mechanism for returning the carriage in the opposite direction, a device for causing the stopping of the return movement of the carriage with the carriage in a predetermined position, means for positioning said device to cause the stopping of the carriage, mechanism for holding said device in stopping position during the return movement of the carriage until the movement of the carriage is completely stopped and machine operated mechanism for releasing automatically said holding mechanism immediately after the movement of the carriage is stopped.

14. In a record making machine, a carriage movable across the machine in advance and return directions, mechanism for advancing the carriage, power mechanism for imparting return movements to the carriage, shiftable means arranged to be set by the operator to cause the arrest of the return movement of the carriage with the carriage in either of two different return positions, mechanism under control of the operator for setting said shiftable means, mechanism for retaining said shiftable means in operative position during the return of the carriage to either of said positions and means operating with the carriage during its return and operated by inertia upon the arrest of the carriage for causing the restoration of said shiftable means to normal position.

15. A record making machine having, in com-

bination, a carriage movable across the machine in opposite directions, means for advancing the carriage, power operated mechanism for returning the carriage, settable stopping means for the carriage, manipulative means to throw the power operated mechanism into operation and to project the stopping means selectively into positions to stop the return movement of the carriage with the carriage alternatively in either of two different positions, mechanism for holding the stopping means, during the return of the carriage, in condition to stop the carriage in the desired position and machine operated mechanism for releasing automatically said holding mechanism after the return movement of the carriage is stopped.

16. In a record making machine, a carriage movable across the machine in advance and return directions, mechanism for advancing the carriage, power mechanism for imparting return movements to the carriage, means arranged to be set by the operator to discontinue the return movement of the carriage with the carriage alternatively in either of two different positions, mechanism for retaining the movement discontinuing means in operative condition during return of the carriage and automatic means rendered operative by the discontinuing of the return movement of the carriage for actuating said retaining mechanism to release said settable means after the return movement of the carriage is discontinued.

OSCAR J. SUNDSTRAND.
